JAMES F. NEALL AND WILLIAM MYERS, OF PHILADELPHIA, PENNSYLVANIA.

Letters Patent No. 77,081, dated April 21, 1868.

IMPROVEMENT IN FURNACE-DRAUGHT REGULATORS.

The Schedule referred to in these Letters Patent and making part of the same.

TO ALL WHOM IT MAY CONCERN:

Be it known that we, JAMES F. NEALL and WILLIAM MYERS, of the city of Philadelphia, in the State of Pennsylvania, have invented a new and useful Improvement in the Regulator for Furnace-Draught; and we do hereby declare that the following is a full, clear, and exact description of the construction and operation of the same, reference being had to the accompanying drawing, making a part of this specification, and to the letters of reference marked thereon.

Our improvement relates to that class of regulators which are operated by the pressure of steam for the purpose of regulating the draught of furnaces by varying the positions of the dampers, or the areas of the air-supplying openings of the furnaces, and has for its objects simplicity and economy of construction, and a diminution of friction, and therefore greater delicacy or sensitiveness in action.

Our invention consists in the construction and arrangement of a hollow steam-cylinder, packing-ring, and piston; so as to operate together, for the purpose, upon a weighted lever, substantially as hereinafter described and specified.

Referring to the drawings, A is the piston, B the cylinder, and C the packing-ring; D a steam-supply pipe, E a weighted lever, and F a case which supports the whole.

The piston A is a hollow cylinder, turned smooth on its exterior sides, closed at its outer and open at its inner end, with the exception of a hollow stem, a', which, opening through the centre of the outer end of the said piston A, extends therefrom concentrically through the latter to some distance beyond its open inner end, say about half the length, more or less, of the said piston. This hollow stem a' is closed at its inner end, so as to afford, also, thereat, a concave bearing, a'', in the said stem, for the conical lower end of a stiff and slender stem, G, upon which the lever above it rests, as shown in the figure.

The cylinder B is, with the case F, cast of metal, and in one piece. It is about three-quarters of an inch, more or less, larger in its inner diameter than the outer diameter of the piston A, and extends, from its open outer end, nearly through the case F, and is closed at this extended end.

The case F is, in this instance, a rectangular oblong box, open below and closed above, and the steam-supplying pipe D passes into this case F, and opens directly into the cylinder B.

The packing-ring C consists of a flat annular piece of oil-dressed raw hide, the inner diameter of which is about three-eighths of an inch, more or less, larger than the exterior diameter of the piston A, and is secured, so as to project concentrically over the edge of the opening in the cylinder B, upon the outer surface of the top of the case F, by means of a flat metallic ring, b', which is bolted firmly down upon the case F, with the packing-ring C partly between, so as to remain steam-tight at the joinings.

The piston A is applied by forcing its open end through the packing-ring C, into the cylinder B, thus turning the projecting inner edge of the packing C inward or downward, and causing it to bear around obliquely against the smooth sides of the said piston. The friction of the packing is consequently less than it would be if caused to slide against the inside of the cylinder B, and it is also much easier to smooth the exterior surface of the piston than the interior surface of the cylinder.

On the upper side of the case F there is a pair of uprights, f', (one only being shown,) having a knife-edge bearing, f'', fixed thereto, so as to serve as the fulcrum of the lever E, whilst a notch, e', in the under side of the latter, serves as the power-point, and receives the knife-edge end of the vertical stem G, whereby the said lever is supported. A movable weight, H, is fitted so that it can be slid along on the lever E, and a safety-guard, I, prevents the lever from being accidentally thrown out of its proper place.

The whole apparatus is intended to be made of suitable metal.

Operation.

The free end of the lever E being connected, by means of wire or jointed iron rods, to the hinged or sliding draught-door or damper of the furnace, the steam-pipe D connected to another communicating with the boiler, and the described regulator filled with water, as heretofore, steam is "let on," and the position of the

weight H then adjusted on the lever E, and fastened with a set-screw, or otherwise, at such a point as will cause it to keep the piston at its mid-length in the packing-ring, when the desired strength of the draught, or position of the door or damper of the furnace has been ascertained; hence any variation in the heat of the furnace will be immediately corrected by the action of the regulator upon the said draught-door or damper, because the movement of the piston A is entirely free from all friction except that necessarily arising from its close contact with the packing-ring C.

Having thus fully described our improvement in the furnace "damper regulator," what we claim as new therein, of our invention, and desire to secure by Letters Patent, is—

The arrangement of the piston A, cylinder B, packing-ring C, and weighted lever E, substantially as described.

JAMES F. NEALL,
WILLIAM MYERS.
